EGRY REGISTER COMPANY, OF DAYTON, OHIO, A CORPORATION OF OHIO

MANIFOLDING MACHINE

Application filed July 29, 1929. Serial No. 381,798.

This invention relates to feeding of paper webs and the like, particularly in devices such as manifolding machines, or the like.

One of the principal objects of the invention is to provide means for supplying a group of loosely arranged superimposed sheets, of selecting from said group each sheet independently of the other, of collating and aligning said sheets successively independently of one another as aligned and delivering into an aligned, collated group.

Another object of the invention is the provision of a feeding device for manifolding or analogous machines adapted during operation to feed the webs to provide a measured web slackness permitting the webs to be thereafter pulled at their issuing ends a distance corresponding to the web feed desired.

Still another object of the invention is the provision of a feeding device of the character mentioned which is constructed as a unit adapted to be readily associated with the web utilizing device, such as a manifolding machine.

Other objects and advantages of the invention will be apparent from the following description and claims and from the accompanying drawings, in which—

Fig. 1 is a side elevation of the invention as embodied in a manifolding machine;

Fig. 2 is a top plan view of the mechanism of Fig. 1;

Fig. 3 is a sectional view of a portion of the mechanism of Figs. 1 and 2, taken on the line 3—3 of Fig. 2;

Fig. 4 is an enlarged fragmentary sectional view along the line 4—4 of Fig. 2;

Fig. 5 is an enlarged detail of the transmission gearing of the device;

Fig. 6 is an enlarged sectional view along the line 6—6 of Fig. 2;

Fig. 7 is a plan view of a modified form of stripper mechanism; and

Fig. 8 is a fragmentary sectional view of the modification of Fig. 7.

For purposes of description and as constituting a preferred adaptation and embodiment of the invention, it is herein illustrated and described in connection with a manifolding machine of well known type. The 50 manifolding machine shown is one known as a billing machine, such as is widely used, in which the paper utilizing device comprises a flat stationary platen and a cooperating, movable typewriter, the platen receiving 55 several superimposed webs of paper or the like arranged as series of connected record blanks, on which the typewriter operates.

As shown the billing or manifolding machine, which is of the flat platen type, is 60 designated generally by the numeral 10; while the paper feeding unit is designated generally by the numeral 11. The portion 10 has a movable typewriter 12 which is adapted to travel or be moved toward or from the 65 operator on the rails 13 and over the platen 14. The rails and the platen are supported by a suitable frame or standard 15. As ordinarily used, machines of this type are adapted to simultaneously record an original 70 and a number of duplicate copies of a bill, memorandum or other paper, the paper webs as shown being supplied from a roll 16 arranged conveniently at the rear of the machine. With such machines the paper is 75 sometimes supplied from a plurality of rolls, or from a stack or stacks of connected blanks.

In accordance with the present invention, means are provided for insuring the proper orderly correlation of the sheets and their 80 proper feeding movement through the machine. Referring particularly to Figs. 1 and 2, the feeding attachment comprises a frame 18 constructed to be attached to the frame of the billing machine, this being accomplished 85 by properly forming the connecting ends of the frame 18 to receive or fit the frame of the billing machine unit 10, suitable clamps 19 being provided to firmly connect the two portions together. A brake roller 18a is piv- 90

totally supported on the arm 18⁰ which in turn is pivotally supported on the frame 18. As shown these clamps are applied to the rear portions of the guide rails 13 which project a considerable distance to the rear of the platen zone. The frame 18 is provided with roll supporting members 20 which preferably have inclined upper edges which serve as ways up which the rolls of paper may be readily rolled to bring the supporting shaft or spindle 21, for the paper rolls, into the supporting journal groove 22. The webs from the roll are extended to pass over suitable rollers and then pass forwardly over the face of the platen 14 with their issuing ends at the front of the paper using machine adjacent the operator. At this end of the machine there is provided a clamp and cut off mechanism comprising a bar 25 adapted to hold the issuing ends of the webs down against the platen, the front edge of this bar serving as a tear off edge so that the operator may conveniently and rapidly sever the sheets or record forms that have been completed. The cut off bar 25 is adapted to be raised to release the issuing ends of the webs by a suitable device such as a foot lever 27 which is connected thereto by suitable linkage so that when the lever 27 is depressed, the cut off bar 25 is raised, and vice versa. A suitable spring 29 or the like is provided to return the bar 25 to its holding position on the web when the foot pedal 27 is released. The holding clips 30 are worked in cooperation with the bar 25, from the pedal through the linkage, to hold the rear portion of the issuing strips in operative positioning within the work device, and to release the webs when it is desired to effect feeding of the webs. The arrangement is such that the clips do not release the sheets, upon operation of the pedal, until after the clamp bar 25 does, and they regrip the sheets before the clamp bar 25 does. As a result the sheets may be drawn or fed the full required distance over the platen, and drawn and held snug and smooth thereover for the typewriting operation.

The number of interrelated sheets used will of course vary with the requirements of the particular conditions encountered in use, but the drawings illustrate an arrangement whereby seven series of forms contained in a single roll are adapted to be moved forwardly across the platen from the supply source in such manner that webs are fed from the roll through the place of utilization in predetermined amount to provide slackness therein, beyond the zone of such feeding, according to the length of the record sheets. This predetermined feeding having been accomplished the operator may release the web clamping means and then pull the strips forwardly to take up the slack in the webs. The arrangement is such that the amount of slack is controlled to provide just the extent of the

webs which needs to be pulled forwardly at their issuing ends to give the desired amount of advancing of the series of forms with reference to the work device. The cut-off bar 25 and the clips 30 being then returned to holding position the operator may tear off the completed record sheets, leaving the next succeeding forms held in position to be properly operated upon.

To provide for suitably feeding the papers to the work end, the feeding unit 11 is used. This comprises as an element a motor 37, suitably mounted upon the frame 18, the shaft of which is operatively coupled to a drive shaft 40. The drive shaft 40 carries a gear 43 which meshes with an intermediate gear 44, which in turn meshes with a gear 45 on a driven shaft 46. The gear 43 is mounted to be readily removed from the shaft 40 so that it may be replaced by a larger or smaller gear, the size of the gear used being dependent upon the amount of feed desired to be imparted to the paper webs. The intermediate gear 44, is mounted upon a sector 46' which is in turn pivotally carried upon the shaft 46, and is provided with a suitable slot and adjusting screw so that as the size of the gear 43 is varied the intermediate gear 44 may be repositioned to properly mesh therewith. Shaft 46 is provided with a belt driving roll 47 which forms a feeding or drive means for belts 48, each of which belts extends partly around its cooperating roll 47 and around a second roll 49 provided adjacent the upper portion of the frame. Two of these belts are shown. Preferably the roll 49 is adjustably mounted so that by means of suitable adjusting screws 50 various lengths of belts may be accommodated. Each of these belts carries spaced feeding members or lugs 55 adapted to pick up and engage within correspondingly spaced apertures 56 in the respective coordinated paper webs, and upon feeding movement of the belts to correspondingly feed the various paper webs. As shown the belts have drive holes therein adapted to receive teeth 57 on the roll 47 to effect positive drive and locking of the belts. Of course sprockets and chains, or other suitable means, for carrying the feeding lugs may be used in place of these belts. In the form of apparatus shown, the distance between successive web apertures is equal to the length of the record sheets, and the lugs 55 are arranged on the belts so that the distance between adjacent lugs on each belt corresponds with the distance between cooperating apertures 56 in the webs, and the lugs are adapted to move in line with the apertures of the webs during feeding operation, one lug coming into engagement with an aperture before the next preceding lug passes out of engagement with its cooperating aperture. In this manner forward feeding of the webs during linear movement of the lugs is effected. The endless car-

- rier members 48 may be arranged for horizontal movement while carrying the paper, or at an inclination as shown in the drawing as best meets requirements.
- 5 For any given installation the belts 48 are arranged for feeding movement, upon actuation, controlled in accordance with the length of the form being used. Preferably the belts are arranged to be started by manually operated control and automatically stopped after a predetermined feeding movement. As shown an electric motor drive with suitable controls is provided so that the operator may start the motor to cause the proper feeding movement of the belts through a desired distance after which the belts are stopped and held locked in position, until the succeeding feeding movement. This permits the operator to pull the issuing ends of the webs to take up the slack thus provided in the webs, while the web clamping means is loosened or released as described above. The motor 37, and the drive connected therewith, may be provided with any suitable control means for manual starting and automatic stopping. The automatic stopping means here used is fully disclosed in a copending application, Ser. No. 420,267, filed January 11, 1930, by William C. Pfeiffer and Frank E. Pfeiffer.
- 10 The details of this automatic stopping mechanism are no part of this invention. The above application shows such a form as is well adapted to be used in connection with the structure defined in the present application.
- 15 As shown a push bar 60 is placed with one end convenient to the operator, which in turn acts through the lever 61 to close an electric switch for the starting of the motor. Associated with the switch and the lever 61 is a suitable control and latch mechanism, not shown in detail, which acts, following actuation and release of the bar 60 by the operator, to effect a predetermined rotation of the drive shaft 40, after which the parts are returned to inoperative position ready to repeat the same sequence of movements. And the drive shaft 40 after it has moved to advance the paper webs from the supply roll 16 towards the platen the required distance, is locked by the control means against further rotation. Control devices for accomplishing such manual starting and automatic stopping and locking of a rotatable roll or shaft are well known in themselves and it is therefore believed the exact construction of the switch, stop and drive mechanism referred to generally and contained in the housing 42, need not be further illustrated or described.
- 20 Mounted on the shaft 46 is a gear 70 which is in driving mesh with an idler gear 71, which in turn meshes with and drives the gear 72, suitably mounted on the frame 18. Also mounted on the frame adjacent the gear 72 are two feeding rolls 73 and 74 which are geared together by means of the gears 75.

One of these gears 75 also meshes with and is driven by the gear 72. The roll 73 is mounted within the frame 18. The roll 74 is mounted within a pair of slidable or tension links 76 each of which has an elongated slot 77 to receive the shaft of the roll 73 and permit movement of the links and the roll 74 under the action of the adjustable tension spring 78 which tends to bring the two rolls 73-74 in engagement. The shaft of the roll 74 extends through elongated slots 79 in the frame 18, which slots permit bodily movement of the roll with respect to the roll 73. Also mounted in the frame 18 is a shaft 85 which passes through the tension link 76 and carries an adjustment cam 86 thereon, preferably formed by flattening the shaft where it passes through the tension links. Suitable operating handle or knob 89 is mounted on the shaft 85, and upon turning of this shaft the links will be moved to separate the rolls 73 and 74. The tension spring 78 urges the links in a direction opposite to the movement caused by the cam 86 and in normal operative position holds the rolls 73 and 74 against each other with properly controlled pressure. The outer sheet or web of paper 90, from the roll 16, is fed between the rolls 73-74, which are separated by the cam 86 when it is threaded between these rolls. During operation the rolls 73-74, being positively driven in accord with the feeding lugs 55, feed the webs from the roll 16 at the needed rate, thus preventing possibility of tearing of the paper by the feeding lugs. This permits of mounting the roll 16 with suitable frictional or other resistance to its turning to prevent uncontrolled unwinding of the paper webs. Under this arrangement all the webs except the outer or driving one will have a bagging or loop, as shown, the amount of which will depend upon the manner in which the forms are wound in coordinated relationship on the roll. After the sheet 90 passes between the rollers 73 and 74, it is looped as at 90a.

Under the action of the feeding rolls 73-74 the webs, which are designated respectively 90, 91, 92, 93, 94, 95 and 96, travel from the supply roll 16 over the auxiliary guide member 97, where they are again brought together in superimposed relationship toward a series of collating rollers. All of the webs engage the first of these rollers which are designated by the numeral 100, the web 90 separating from the other webs at this point and travelling down around this roller 100 and under the next succeeding roller 100, over which the next web 91 passes. The other webs travel in similar manner, each passing down around its own roller and under the next succeeding one so that each web is guided individually by one of the rollers 100. Each web is therefore first separated from the other webs and then brought into super-

imposed relationship with the previously separated webs to again stack or arrange them in grouped relationship along the belt 48. The apertures 56 of each of the various webs are therefore engaged by the lugs 55 while the web is separated from frictional or other impeding association with the other webs so that each web is thus free for such minor movement or adjustment as will cause the lugs to squarely and certainly pick up the web and properly position it upon the feeding lugs in proper adjusted relationship with all the other webs. The rollers 100 are provided with suitable grooves 101 into which the lugs extend as they pass beneath the rollers, these grooves permitting the forward movement of the pins so the latter may engage the paper webs beneath the rollers as the pins move by. The arrangement of the parts shown in Fig. 4 illustrates the apertures of the webs 90 and 91 in engagement with the lugs 55. The apertures in web 92 are about to be engaged by the lugs, and while being thus engaged it will be apparent that this web will be shifted slightly if need be, with relation to the other webs, the low frictional resistance due to the separation of the sheets readily permitting this, so that it may be brought into registration with the lug position in case it is not already in that relationship. The apertures in the webs 93, 94, 95 and 96 have not yet been picked up by the lugs 55, but these will be picked up successively as the lugs move while advancing the sheets towards the platen zone. The holes in all the webs will thus be brought in registration when the webs have been picked up on the feeding lugs, before the webs are advanced to the platen by the pull of the operator, and the record sheets are therefore coordinated and properly stacked so as to be in their proper relationship with respect to one another. When the operator pulls the papers toward him he is thus assured that the record sheets pulled onto the platen will be properly coordinated.

The particular mechanism shown for rotating the paper roll and for interim adjusting of the sheets of paper during feeding is not claimed herein as it forms the subject matter of a companion application of William C. Pfeiffer and Frank E. Pfeiffer filed of even date herewith Serial No. 382,034.

As the papers, properly stacked on the feed belts, travel towards the platen together they are positioned on the lugs 55, from which they need to be removed. As shown in Figs. 3 and 6 the roller 49 over which the webs pass serves to strip the sheets from the lugs and to facilitate their proper feeding into the loop 106. This roller 49 is grooved at 110 to receive belts 48. Above the upper portion of each belt adjacent this roller is a guide strip 111 which prevents the webs from rising off of the pins until the

paper is about to engage the roller 49. As the paper rides over this roller the lugs are moved out of the apertures, as the belts are in the grooves while the paper is carried over the roller surface. The lugs therefore cannot tend to carry the webs around the roller. An additional advantage in this arrangement is the frictional drive which is given to the paper by reason of the surface of the roller 49, this frictional drive tending to push the paper along even after the lugs 55 are entirely freed from the paper apertures.

The two belts 48 when operatively stretched between the two rolls 47 and 49 provide two flat surfaces for holding the forwardly feeding papers. A space 105 of substantial size is provided between the rear edge of the platen zone and the upper or forward portion of the belts 48, this space being provided to accommodate that slackness in the webs which results from such forward feeding, the webs being permitted to hang in a loop as indicated at 106 in Fig. 1, until the issuing ends of the strips are pulled by the operator to withdraw used forms from the machine and properly position fresh sheets or blanks over the platen.

It will now be understood that the operator, after finishing one group of record sheets, and desiring to remove them from the series of webs and move a fresh group of blanks into position on the platen, first pushes the control 60. The motor 37 is thus caused to operate the feeding mechanism, and the lugs 55 are moved by the belts 48 through a distance previously arranged for and corresponding to the length of the record forms being used. Since the paper holding means within the platen zone is at this time in paper holding position this produces the slackness 106 of the proper amount, corresponding to the length of the record sheets. The work operation having been finished, the operator then depresses the treadle 27 to release the completed forms and pulls forwardly on the issuing ends of the webs to completely take up this slack. Since the belts 48 and feeding lugs 55 cannot move at this time, as they are definitely held by the lock mechanism provided as part of the motor control mechanism, when the slack is all taken up the paper web can be pulled no further and will then have been advanced over the platen the proper distance for the length of a blank or record being used. On release of the treadle the cut-off bar 25 then returns to its operative or holding position with its edge positioned for severing the completed forms.

A further advantage in the arrangement for individually stacking the sheets on the lugs or feeding means lies in the convenience and facility with which the various webs are first threaded through or applied from the roll 16 to the platen. The first web 90 may

be conveniently pulled around the guide member 97 and up and over the guide roller 100. When the apertured end of the sheet is about to be inserted under the next roll 100, the belt 48 may be advanced manually to pick up the apertures in the sheet and pull this sheet under the roll 100. The next web 91 is then applied in turn to guide member 97 and roll 100 and its apertures 56 may then be individually picked up by the lugs 55 which may be moved the short distance required for this purpose. Each sheet is thus picked up individually and they are then fed forwardly in exact registration.

15 In Figs. 7 and 8 is shown a different form of stripper mechanism. In this modification the upper roller 49' is provided with grooves 110', but these grooves are only sufficiently deep to serve to receive and guide the belts 20 48; the diameter of the roll 49' in general being substantially uniform throughout. To effectively strip the paper webs from the lugs 55 a stripper plate 113 is provided, which as shown has a portion projected backwardly between the two belts, and beneath the belts. When the paper webs are threaded through the machine, the forward ends will thus ride forwardly over the rear portion of the stripper plate, which is so proportioned 25 and positioned as shown in Fig. 8 that the paper webs will be completely lifted from the lugs before these lugs start their reverse movement around the upper roller 49 in connection with the rearward travel of the lower part of the belts. As shown this stripper plate is of light metal and has its lower end 114 bent around a supporting bar 112 which is suitably mounted in the feeding unit frame. By properly forming this curved portion the 30 stripper plate may be readily snapped into and out of position.

While the forms of apparatus herein described constitute a preferred embodiment of the invention, it is to be understood that the invention is not limited to these precise forms of apparatus, and that changes may be made therein without departing from the scope of the invention which is defined in the appended claims.

50 What is claimed is:

1. In a machine for collating paper, means for delivering a plurality of superimposed sheets, means for separating said sheets, a collating means, and means for applying said sheets to said collating means separately and independently one of the other.

2. In a machine for collating paper, means for delivering a plurality of superimposed sheets, means for separating said sheets, a collating means, and means for applying said sheets to said collating means independently one of the other and successively in superimposed relationship.

3. In a machine for collating sheets, means for delivering a plurality of superimposed

sheets, a collating means and means for delivering each of said sheets independently one of the other successively to collating position.

4. In a machine for collating sheets, means for delivering a plurality of superimposed sheets, a collating means and means for delivering each of said sheets independently one of the other successively to collating position, and means for maintaining said sheets in collated position in superimposed relationship.

5. In a machine for collating sheets, means for delivering said sheets in superimposed relationship as a group, and means to separate said sheets one by one from said group, a collating means, and means to mount said sheets one by one successively on said collating means to assemble said sheets in a second superimposed aligned group.

6. In a machine for collating sheets, means for delivering said sheets in superimposed relationship as a group, and means to separate said sheets one by one from said group, a collating means, and means to mount said sheets one by one successively on said collating means to assemble said sheets in a second superimposed aligned group, said collating means being arranged to receive each of said separate sheets independently of the other at different positions with respect to the first mentioned group.

7. In a machine for collating sheets, means for conveying the sheets in a superimposed group, means for separating from said group said sheets one by one, a collating means arranged to receive each of the said sheets successively independently of the other sheets for assembly in a second aligned group, and means to move said groups simultaneously continuously.

8. In a machine for collating sheets, a continuously traveling collating means and means to feed a plurality of sheets thereto successively independently of one another as the collating means moves whereby the sheets will be grouped in the collating means in alignment but each sheet being independently collated.

9. In combination in a machine for collating sheets, a moving belt, spaced collated studs thereon, a plurality of superimposed vertically and laterally spaced separating rollers over said belt having means through which said studs can pass through said rolls and means of delivering a group of sheets to said rolls, each sheet being separated from said group by passing between adjacent rolls and independently delivered to the studs and belt while being maintained thereon after being mounted on the studs and belt by said rolls.

10. In a machine for collating sheets, a belt, collating studs thereon, rollers extending below the height of said studs arranged

in spaced relationship over said belt at different heights therefrom, and means of delivering a group of sheets to be separated by said rollers and independently successively mounted on said collating studs into an aligned group, said rolls being adjusted to retain said sheets on said belt and stud.

In testimony whereof we hereto affix our signatures.
